UNITED STATES PATENT OFFICE.

GEORGE F. JACOB, OF EVANSTON, ILLINOIS.

HEAD LAMP FOR MOTOR VEHICLES.

Application filed July 22, 1927. Serial No. 207,724.

This invention relates to automobile lamps. Particularly it relates to the arrangement and construction of the light reflecting portions for the main head lamps for automobiles.

One of the objects of the invention is the provision of a lamp structure for carrying the light bulb, and one that can be bodily removed from the lamp casing at will.

Another object is the provision of a light reflecting structure for condensing the light rays and projecting the same in a flat beam upon the road ahead and without being thrown into the eyes of the driver of an approaching car.

Still another object is to furnish a lamp structure in which a reflector portion may be readily removed on occasion.

Again, an object lies in a novel form of light-bulb holding means by which accuracy of bulb adjustment is possible as well as for securing said bulb firmly in position.

In addition, an object is that of providing a reflector portion bent up from sheet metal into novel form.

In the appended drawings,

Figure 1 is a front elevation of a lamp body showing my invention installed therein.

Figure 2 is a longitudinal section of the same in elevation.

Figure 3 shows a reflector portion structure in perspective, as seen from the rear, separated from the lamp casing.

Figure 4 is a transverse section of the structure shown in Figure 3 taken on line 4-4 of that figure, and

Figure 5 shows part of the structure of Figure 3, in perspective, as it appears during forming operations.

Besides the novel construction believed to be present in my device as illustrated and to be described, the invention seeks to go somewhat farther than the device forming the subject of my pending patent application for automobile lamps filed March 17, 1927 under Serial Number 176,134.

In Figures 1 and 2 the character 1 designates a lamp casing or drum having any usual lens 2 held in place at its front side by the common retaining ring 3.

My invention is comprised in a structure adapted to slidably fit into the casing 1, such structure carrying the usual light bulb, the whole being firmly anchored in the casing by the bulb holding socket as will ap-

pear. In Figure 4, for example, the mentioned structure includes a flat bottom portion 4 of metal having side walls 5 bent up therefrom, portions of both the bottom and sides being lapped upon one another as at 5' as shown also in Figure 3, said sides lying closer to one another at their rear ends than at their forward ends as may be seen by a study of Figure 1, the edges resulting from lapping the parts being parallel for a purpose to appear. Part of the bottom 4 is upturned at the rear end as at 6 and its edge is recurved about as shown in Figure 5 to form a groove 6' facing forwardly.

As shown in both Figures 2 and 3 part of the top edges of the sides 5 slope downwardly toward the rear while their top edges forward thereof are substantially parallel with the bottom 4 and have overturned edges 9 to engage a part 10 as a closure for the upper side of the structure. In one form of my invention the said part 10 may include an upwardly and forwardly extending arched portion 11, or as in Figures 1 and 2 this portion 11 may be replaced by a glass 11'. The said bottom 4 may include a downwardly and forwardly extended arched portion 12 best shown in Figure 2. The sides 5 at their rear edges are formed each with an ear 13, Figure 5, and these are lapped upon the rear end 6 as shown in Figure 3 creating a very rigid arrangement. In the bottom 4 is a circular opening 4' into which a semi-spherical reflector 14 is adapted to be placed, the usual flange 15 thereof adapted to rest upon the upper surface of said bottom. As thus constructed the box-like device is intended for insertion into the casing 1. Since the edges of the described lapped portions at 5' are parallel when placed in said casing the resultant flanges will lie squarely upon the cylindrical wall of the same as illustrated in Figure 1, the distance between said edges naturally governing the position and height at which the inserted structure will lie. In the present instance the width of the bottom measurement from edge to edge is such that said structure will lie where the portion 12 just reaches the casing behind the retaining ring 3 and the portion 11, or 11' as the case may be, fits against the top wall of the casing also just behind said ring 3.

The reflector 14 is designed to rest upon the lower wall of the casing 1 while its said flange 15 rests upon the bottom 4 as already

- described, and here again it is to be noted that the position of the structure carrying the bottom must be so located that when the reflector is drawn downwardly upon the casing by means about to be described the said flange 15 will bear strongly upon said bottom. A tapered, threaded and split fitting 16 extends through the reflector and casing and has a flange 17 to rest upon the former, 5 while a nut 19 screws upon such fitting against said casing creating a clamping structure. A tube 20 fits snugly within the fitting 16 and is clamped by the latter, split at 18, by a nut 21 screwed thereon. The said 10 tube 20 receives at one end the usual bulb 22 and at the other the attachment plug 23 carrying the conducting cord 24.

It is quite well known that in devices of this nature the parts carrying the lamp or bulb are difficult to adjust by reason of the location thereof as well as being difficult to hold in proper position due to the means employed. However, as I construct the parts the adjustment can be made outside the casing 1 and the effect watched as to the image cast upon a wall while making such adjustment. By loosening the nut 21 the tube 20 may be raised or lowered to properly focus the light, and may also be rotated to obtain 25 the exact effect desired and then may be firmly clamped by the means described with little likelihood of being disturbed.

The inturned edges 7 of the sides 5 of the device are designed to receive a mirror or reflector 8, the latter resting as well in the recessed portion 6' of the end 6 and said mirror or reflector lies at an angle of about 45° to the bottom 4 and the light rays from the reflector 14 are therefore cast directly forward. By releasing the reflector 14 the whole structure may be drawn out of the casing 1 and the said reflector 8 may be withdrawn for cleaning or for substituting another.

The purpose in making the structure in substantially the form shown is that the light rays will all be confined in a relatively small space and thus condensed or intensified. Said structure is relatively low in height and the reflector 8 is well back so that the light rays will be confined and projected straight ahead rather than upward.

In the top of the casing 1 above the described structure is a lamp 25 supported in a tube 26 whose rear end extends through the back wall of said casing and receives a conducting cord 27 which, together with the cord 24 may be connected in the usual way with suitable switches, not shown, for operating the lights as required. The lamp 25 may be employed for "parking" purposes and to this end the glass 11' before referred to is used in lieu of the portion 11 of Figure 3. Said lamp may also be used as a direction light or for other purposes not necessary to enumerate herein. A glass 28 may be

placed in the top of the casing 1 above the lamp 25 by means of which the driver may easily determine whether or not said lamp is lighted.

While the removable structure carrying the reflectors 8 and 14 may be preferably bent into form it may, of course, be otherwise constructed, as to method of manufacture.

Due to the manner of securing the affair in position vibration noises cannot result.

The reflector 14 and bottom 4 may be made integral, of course, but preferably these are separate parts.

I claim:

1. The combination with a casing for the head lamp of a motor car, and a flanged primary reflector and its lamp secured at the bottom of said casing arranged to direct light rays upwardly toward the top of said casing, of a secondary reflector structure of box-like form insertable in the casing including a bottom portion having an opening to receive the said primary reflector, the flange of the latter bearing upon said bottom at said opening securing said secondary reflector in place, parts of the bottom at diametrically opposite sides of the opening adapted to rest upon the casing in lines paralleling the longitudinal line of said casing, thence extending away from said bottom forming opposite side portions for said secondary reflector and terminating each in a flange disposed at an angle of substantially 45° to said bottom, and a reflector plate 105 slideable beneath the flanges and facing at an angle the open front of said casing.

2. In combination, a reflector for a head lamp casing comprising a body of sheet metal including a bottom portion having an opening therein, the metal at diametrically opposite sides of the opening extending away from said bottom portion forming the sides of said body, said sides terminating each in a flanged edge part of which lies at an angle of 45° to the plane of said bottom and adapted for receiving a reflector plate slidably therebetween, said bottom having an extension at each edge lying between said sides, one of said extensions lying substantially at 110 right angles to said bottom at one side thereof and at its ends engaging the said sides and forming a stop for said reflector plate, the other extension being directed away from the plane of said bottom at an angle from its under side, and a part engaging the said flanges of said sides adjacent the reflector plate and including an extension lying at an angle thereto, the last named extension and the said angling extension of said bottom 120 conforming to and adapted to abut the inner walls of said casing.

In testimony whereof I affix my signature.

GEORGE F. JACOB.
